UNITED STATES PATENT OFFICE.

EDGAR LEE DAVIS, OF WEST FRANKFORT, ILLINOIS.

INTERNAL-COMBUSTION ENGINE.

Application filed July 13, 1923. Serial No. 651,192.

To all whom it may concern:

Be it known that I, EDGAR LEE DAVIS, citizen of the United States, residing at West Frankfort, in the county of Franklin and State of Illinois, have invented certain new and useful Improvements in Internal-Combustion Engines, of which the following is a specification.

This invention relates to internal combustion engines, and has particular reference to the provision of an improved valve operating mechanism employed in such engines.

The primary object of the invention is to provide a valve operating mechanism embodying rocker arms having their opposite ends directly associated with the cams and valve stems so that the usual push rods are eliminated, thereby lessening the cost and number of parts involved in valve mechanisms of this kind.

Another object of the invention is to provide a valve operating mechanism wherein a minimum number of parts are provided which are liable to require adjustment or renewal, and by means of which efficient actuation of the valve will be had.

Other objects will appear as the nature of the invention is better understood, and the same consists, in the novel form, combination and arrangement of parts hereinafter more fully described, shown in the accompanying drawings and claimed.

In the drawings, wherein like reference characters indicate corresponding parts throughout the several views,

Figure 1 is an end elevation of a valve operating mechanism constructed according to this invention.

Figure 2 is a fragmentary longitudinal sectional view of the upper end of one of the rocker arms, and

Figure 3 is a fragmentary view, partly in section, and partly in side elevation showing the lower portion of one of the rocker arms and adjacent parts of the engine.

Referring more in detail to the several views, 5 indicates an engine block of any ordinary or preferred construction having a crank case at the lower portion thereof which embodies a removable lower section 6 and in which is journaled the longitudinal cam shaft 7 having the usual cams fixed thereon for operating the supply and exhaust valves, one of which cams is shown by dotted lines at 8 in Figure 1.

Mounted upon the top of the block 5 is a detachable head 9 containing the supply and exhaust ports adapted to be controlled by the usual mush room valves whose stems 10 are disposed horizontally and project outwardly through one side of the head as shown in Figure 1. The adjacent side of the engine block is provided with a series of shaft hangers 11 which support a shaft 12 upon which the rocker arms 13 are mounted, said shaft hangers 11 being spaced apart substantially the distance required for the width of the rocker arm. The rocker arms are thus vertically disposed and are provided with inwardly extending lower end portions 14 which are preferably provided with anti-friction rollers 15 engaging the cam 8.

In order to provide a dust-tight joint in the crank case where the lower ends 14 of the rocker arms extend into the same, suitable vertical slides 16 are snugly fitted onto the ends 14 of the rocker arms and mounted for vertical movement in guide ways 17 provided adjacent relatively large slots 18 in the crank case. It will thus be seen that when the rocker arms are actuated, the slide plate 16 will reciprocate in the guide ways 17 and maintain the slots 18 closed at all times.

The valves employed are preferably spring seated outwardly by means of springs 19, in the usual manner, and the upper ends of the rocker arms are provided with inwardly projecting internally threaded bosses aligned with the valve stems 10 and carrying adjustable bolts 20, the inner ends of which engage the outer ends of the valve stems 10 so that the valves will be opened and allowed to close at proper intervals when the rocker arms are actuated by the cams 8.

The bolts 20 are threaded through the bosses of the rocker arms, which bosses are denoted by the reference numeral 21, and suitable jamb nuts 22 are threaded upon the bolts 20 at opposite ends of the bosses 21 for maintaining these bolts in adjusted position. It will thus be seen that by adjusting the bolts 20 inwardly toward the valve stems, any wear which is experienced in the parts of the valve mechanism will be taken up for eliminating the usual tapping action which occurs in devices of this kind.

From the foregoing description it will be seen that I have provided a very simple

and efficient form of valve operating mechanism embodying rocker arms having their ends directly engaged with the actuating cams and the valve stems, so that the use 5 of push rods between the rocker arms and the cams is rendered unnecessary. Also, the parts are so disposed as to render access to the same convenient when repair or replacement of parts is found necessary or 10 adjustment required. The rocker arms may be provided with grease cups 23 for lubricating the parts where these rocker arms are mounted upon the shaft 12.

Minor changes may be made without departing from the spirit and scope of the invention as claimed.

What I claim as new is:

In an internal combustion engine, having a cylinder and a crank casing with a cam 20 shaft journaled therein, said crank casing

being provided at its side with an opening, a hanger attached to the side of the cylinder and having a bearing, a rocker arm having a shaft which is journaled in the bearing, the rocker arm being provided with a 25 rectangularly disposed extremity which passes through the opening in the side of the crank casing, said extremity being integral with the rocker and operatively engaging the cam shaft, a slide member having a 30 central opening which snugly receives said extremity, guides for holding the slide member over the opening in the crank casing, and adapted to guide the movement of the slide member, a bolt adjustably mounted 35 at the opposite end of the rocker and engaging the stem of a valve of the engine.

In testimony whereof I affix my signature.

EDGAR LEE DAVIS.
